UNITED STATES PATENT OFFICE.

MAURICE LACHMAN, OF NEW YORK, N. Y.

METALLIC FABRIC FOR FENCES AND OTHER STRUCTURES.

1,051,126.

Specification of Letters Patent. Patented Jan. 21, 1913.

Application filed November 4, 1910. Serial No. 590,674.

To all whom it may concern:

Be it known that I, MAURICE LACHMAN, a citizen of the United States, and a resident of the city, county, and State of New York, have invented certain new and useful Improvements in Metallic Fabric for Fences and other Structures, of which the following is a specification.

This invention relates to metallic fabric suitable for fences, grills, partitions, grating, concrete reinforcements and a variety of other purposes.

One of the objects of the invention is to produce a metallic fabric of intersecting members and to secure them together by means which will effectively prevent water or moisture getting at the places of intersection, and thus preventing rust at said places.

Another object is to provide a metallic locking clip which may be compressed under great pressure around the said members at the places of intersection and swaged into the interstices and corners formed by the intersection of the members to form a rigid structure with the elements pressed into a substantially homogeneous mass at the place of intersection, without weakening any of the elements.

Another object is to produce a fabric of maximum strength while being comparatively light and which may be rapidly and economically produced.

Other objects will appear from the hereinafter description.

The invention will be understood from the description taken in connection with the accompanying drawing, in which:

Figure 1 is a section of the fabric made according to my invention, the parts forming the fabric being shown on a smaller scale than in the other figures. Fig. 2 is a view of the intersecting members and fastening clip of the finished fabric. Fig. 3 is a section on line 3 of Fig. 2. Fig. 4 is a view similar to Fig. 2 with the fastening clip provided with fins. Fig. 5 is a section on line 5 of Fig. 4. Fig. 6 is a perspective view of one form of the locking clip. Fig. 7 is a perspective view showing the intersecting members and the clip illustrated in Fig. 6, assembled before they are swaged together to form the finished fabric. Fig. 8 is a perspective view of a slightly modified form of clip. Fig. 9 is a perspective view showing

intersecting members and the clip illustrated in Fig. 8, assembled, before being swaged together.

The same reference character indicates the same part in the several views of the drawing.

The cross members consist of the wires A and B which are here shown of different sizes, although they may be of the same size. While they are shown as circular in cross-section, they may be of other suitable shape as well as size. Preferably, each of these wires are crimped to form offsets a and b, respectively, at the place of intersection, although in some constructions only one of the wires may be offset, and in other constructions both wires may be without offsets. These offsets may be placed in both wires, A and B, before they are assembled, as shown by Fig. 6, or the offsets may be placed in only one wire, A, as shown by Fig. 9, and the offsets in the wire B, may be formed when the clip is swaged around the two wires at the place of intersection to lock the parts together.

The locking clip C is made of hard, ductile metal preferably sheet steel, capable of being bent in the form desired, as here shown U-shaped, and adapted to be molded or swaged under great pressure. The sides C' of the clip are provided with the holes or openings c, here shown as circular, but may be of any shape suitable to receive the member B. A slot may extend from each of said openings c, to the free end of each of the sides formed on each of said side fingers c², as shown in Fig. 6.

In forming the fabric, one of the wires, A, for example, is placed between the sides C' of the clip and at the bottom thereof with the offset a under the holes c. The other wire B is inserted through the slots c² between the fingers c² and into the opening c, with its offset b interlocking with the offset a, in the wire A. The parts, thus assembled, are shown in Fig. 7. As thus assembled, the parts are placed between dies or swaging blocks having suitable forms therein, which are forced together, and great pressure is applied to compress together the wires at the point of intersection, to force the metal of the clip into angles or spaces 20 formed by the wires A and B, and tightly around the wires at 21, and into the interstices formed by the intersection of the wires.

This substantially joins the clip together as though it were an integral piece and also joins it to the intersecting wires and the wires themselves into a compact, rigid, substantially integral body, leaving no joints, 5 seams or openings through which water or moisture can reach the wires where they intersect to cause rust. The dies may be and are preferably formed so that the finished 10 joint will be symmetrical on each side. They may also be formed so that fins f may be left on the locking clip, as shown by Figs. 4 and 5. These fins act as additional bracings between the strands or wires A, B.

15 In the construction shown by Figs. 8 and 9, the clip C' is not provided with slots c' , as shown in Fig. 6. When this clip is used, the wire A is seated therein with the offset a between the sides thereof. An end of the 20 wire B, which in this case may not be provided with an offset b , as shown in Fig. 7, is then inserted a suitable distance through the openings c in said clip. When the parts are thus assembled, and as shown by Fig. 9, 25 the dies are forced together and the parts compressed and swaged as hereinbefore described. During the operation of swaging, the wire B may be and preferably is pressed against the wire A with such force that an

offset is formed in the wire B, which inter- 30 locks with the offset a .

Having now described my invention, what I claim as new and desire to secure by Letters Patent is:

1. A metallic fabric for fences and other 35 structures, consisting of intersecting members, and a clip surrounding the members at each place of intersection, said clip and members at the place of intersection being compressed to form substantially a homogeneous joint. 40

2. A metallic fabric consisting of intersecting members, and a clip surrounding the members at each place of intersection, said 45 clip and members at the place of intersection being compressed to form substantially a homogeneous joint, said joint provided with fins projecting therefrom between and in the plane of the members.

In witness whereof I have hereunto set 50 my hand at Long Island City, county of Queens and State of New York, this 26th day of October, 1910.

MAURICE LACHMAN.

In presence of—

REGINALD HAWLEY,
MARGARET KELLEY.
